UNITED STATES PATENT OFFICE

EDWARD LASKER, OF CHICAGO, ILLINOIS

BREAST PUMP

Application filed January 26, 1925. Serial No. 4,942

My invention relates to breast pumps and it has for its object to provide a new and improved form and arrangement of parts for producing and controlling the vacuum by the force of which the operation of the device is effected. It is one of the objects of my invention to provide controlling means for the application of the force of the vacuum independently of the production of the vacuum so that a suction of constant power may be utilized for exerting its force intermittently so as to provide rest periods between successive periods of action. It is another object of my invention to provide an arrangement of parts comprising a controlling mechanism of the type described and comprising means by which air under light pressure is supplied at the rest periods for exerting a massaging effect whereby the gland is stimulated beneficially for rapidly increasing milk production and for relieving the blood congestion caused by the vacuum.

It is another object of my invention to improve devices of this type in sundry details hereinafter pointed out. The preferred means by which I have accomplished my several objects are illustrated in the drawings, and are hereinafter specifically described. That which I believe to be new and desire to cover by this application is set forth in the claims.

In the drawings:

Fig. 1 is a view, partly in section, and more or less diagrammatic, showing an approved form of my invention.

Fig. 2 is an enlarged detail view of the breast appliance, being shown in section; and

Fig. 3 is a view partly in section and more or less diagrammatic, showing a modified form of my improved mechanism.

Referring particularly to Figs. 1 and 2, 10 indicates an ejector of any approved type adapted to be connected by means of a coupling device 11, with a faucet 12 of the usual style, through the medium of which a stream of water of variable size can be forced through the ejector 10, serving to draw air toward the right in Fig. 1 through the branch pipe 13. The pipe 13 is connected by means

of a flexible tube 14 with a receptacle 15 which is shown in the form of a bottle. A breast appliance 16 is mounted in the closure 17 of the receptacle by means of a hollow shank 18, whereby the suction exerted upon the pipe 13 by the ejector 10 is applied at the mouth of the breast appliance 16.

Upon the pipe 13, there is mounted a pressure indicator 19 of any suitable type by which the effective force of the vacuum can be determined. A relief valve device 20 is also provided, comprising a cap 21 provided with an opening 22 in its outer end, a ball 23 being held in position for closing the opening 22 by a coiled spring 24, the effective strength of the spring 24 upon the ball 23 being controllable by the adjustment of the cap 21 upon the valve device 20, the adjustment in the construction shown being effected by the use of screw threads. As will be readily understood, when the force of the vacuum exceeds a certain predetermined strength, the ball 23 will be unseated against the action of the spring 24, permitting the entrance of air.

Means is provided for interrupting the action of the vacuum upon the breast appliance, such interrupting means in the construction shown comprising an opening 25' which may be interposed at any convenient point in the tubular connections between the vacuum creating means and the vacuum chamber 15, this opening being normally closed but adapted to be opened at intervals to destroy the vacuum in the apparatus. Any means may be used to intermittently close this opening 25', this means being here shown as a valve 25 carried by a spring arm 26 mounted upon the pipe 13, the spring 26 serving to hold the valve 25 yieldingly in position for closing an opening in the wall of the pipe 13. An electro-magnet 27 is positioned opposite the spring 26 which is provided with an armature 28 adapted to be attracted by the magnet 27 for raising the spring 26 and carrying the valve 25 out of its operative closing position. The magnet 27 is operatively connected with a battery 29 or with some other suitable source of electrical energy, a commutator 30 being inter-

posed in the circuit connecting the magnet with the battery. The commutator 30 is adapted to be driven at the desired speed by means of a shaft 31 which is to be rotated 5 manually or by any suitable driving means as may be desired.

In operation, the breast appliance 16 is applied to the breast of a patient in the well known manner, while the faucet 12 is opened 10 so as to produce a suction effect through the pipe 13. At the same time the shaft 31 is driven for making and breaking the electrical connection between the battery 29 and the electro-magnet 27. During the time when 15 the valve 25 is in the position as shown in Fig. 1, a suction is exerted through the tube 14 and the vacuum chamber 15, causing the milk to be drawn into the vacuum chamber 15 which serves as the milk receiver. The 20 pressure, which is determined by the gauge 19 is controlled by the regulation of the stream of water passing through the faucet in the usual manner. The relief valve device 25 serves merely for providing a maximum force of vacuum, the relief valve being adapted to function only when there is a tendency to exceed such predetermined maximum force. As the commutator 30 rotates, the circuit through the magnet 27 is broken at intervals, permitting the valve 25 to move into the position as shown in Fig. 1 for rendering the force of the vacuum effective upon the 30 breast appliance. At alternate intervals, the magnet 27 is energized, serving to move the 35 valve 25 upwardly for permitting air to enter freely to the interior of the pipe 13, serving thus to relieve the suction upon the vacuum chamber 15 and the breast appliance 16. By 40 this means, alternate periods of operation and rest are provided. The length of the periods of operation is of course controlled by the rate of rotation of the shaft 31 upon which the commutator is mounted.

It is ordinarily preferable that the periods 45 of operation and rest be as regular as possible, such regularity contributing materially to the stimulation of milk secretion. For this reason, it is important that the shaft 31 be driven at a constant rate, and suitable means 50 for effecting this result is preferably to be supplied.

The breast appliance 16 is funnel-shaped, being preferably in the form of a cone continuously from the edge at the mouth of the 55 appliance substantially to the apex where the suction opening from the body of the appliance into the shank 18 is comparatively much smaller in diameter than that of the nipple of the breast of the patient. The 60 angle of the opening of the cone of the breast appliance is preferably to be less than 90° and is to be large enough to permit the breast of the patient to be inserted well within the appliance, so as to bring the nipple of the 65 breast preferably in close proximity to the

apex of the cone. In this way, the appliance serves to support the breast and the nipple so as to prevent any material distension, while at the same time permitting effective operation for the extraction of the milk.

70

Referring now to Fig. 3, in which a modified form of construction is illustrated, similar parts are indicated by the same reference characters. In the modified form, the vacuum chamber 15 and the parts connected therewith are the same as those above described, except that a relief valve 32 is provided in addition. This valve 32 is in the form of a tapered tube of flexible material such as rubber, the outer end of which is slit at 33. The construction is such that the slit 33 is normally closed, and held closed by a light yielding pressure, so as to prevent the entrance of air downwardly therethrough. The device is adapted to open, however, so as to permit the escape of air in case the interior pressure in the valve 32 rises higher above the atmospheric pressure than desired.

75

In the construction shown in Fig. 3, a rotary pump 34 is utilized for providing the desired vacuum, such pump being driven in the construction shown, by a motor 35 of any suitable type. A worm 36, mounted upon the motor shaft 37 drives a worm gear 38 mounted upon a shaft 39, the shaft 39 being provided with a crank arm 40 which is connected by means of a pitman 41, with the arm 42 of a valve 43 mounted within a valve case 44, located in the connections between the pump 34 and the vacuum chamber 15. As is clearly shown in said Fig. 3, the valve casing 44 is connected with both the suction side and the pressure side of the pump 34 by means of short pipes 45 and 46, respectively, the arrangement being such that the tube 14 leading from the vacuum chamber 15 is adapted to be connected alternately with the suction side and the pressure side of the pump as the valve 43 is given the rotary movement by means of its connection with the gear 38. The operation of the device as shown in Fig. 3 is substantially the same as that above described, except that during the periods of rest the vacuum chamber 15 is connected with the pressure side of the pump so as to provide a slight pressure within the breast appliance 16 above that of the atmosphere as compared with the atmospheric pressure within the breast appliance 16 of the device of Fig. 1. By the provision of this slight excess of pressure within the breast appliance in the device of Fig. 3, a massaging effect is produced upon the gland of the breast of the patient, serving to stimulate the gland beneficially for bringing about rapid stimulation of milk secretion and relief from blood congestion. The amount of pressure delivered upon the breast through the appliance 16 is of course controlled by the degree of force required for opening the relief valve 32.

While I prefer to embody my invention in one of the forms as illustrated in the drawings, it will be understood that I do not desire to limit myself to the details of such constructions, except so far as the claims hereinafter presented are so limited, inasmuch as it is evident that changes might readily be made in the forms of the mechanism without departing from the spirit of the invention.

10 I claim:

1. A breast pump comprising a vacuum chamber, a breast appliance connected therewith, means connected with said chamber for exhausting air from the chamber and the breast appliance, a valve interposed between the exhausting means and the mouth of the breast appliance for quickly eliminating the vacuum on said breast appliance, an electromagnet adapted when energized to operate said valve, a commutator connected with said magnet and with a source of electrical energy, and means for actuating said commutator for giving said valve an intermittent operation in the desired timed relation.
- 25 2. A breast pump comprising an ejector for producing a continuously acting suction, means for connecting said ejector to a source of running water for operation by a stream of water passing therethrough, a receptacle, a closure for said receptacle, a tube composed of rigid and flexible parts passing through said closure and connected to the suction end of the ejector for the exhaustion of the receptacle, said tube having a projection thereon, said projection having an opening therein forming a vent enabling interruption of the exhaustion of the receptacle and a rigid tube extending through said closure, said tube being bent and having a flaring, conical shaped 40 inlet for application to the breast.

EDWARD LASKER.
